PORTABLE DERRICK

Howard D. Hilborn, Houston, Tex., assignor to
 Emsco Derrick & Equipment Company, Los
 Angeles, Calif., a corporation of California

Application August 12, 1944, Serial No. 549,256

8 Claims. (Cl. 189—15)

1

This invention relates to portable derricks and it has special reference to a system and means for elevating a derrick from one position to another, or from a substantially horizontal position to a substantially upright or vertical position. The invention is especially applicable to four legged derricks, arranged to be raised by cable as distinguished from those which are adapted to be raised by hydraulic or mechanical means.

An object of the invention is to provide a system or arrangement for elevating and lowering derricks in which the line pull is considerably reduced and the stress in the several members comprising the derrick is substantially decreased.

Another object of the invention is to provide an elevating and lowering system for derricks in which accessory instruments such as trusses, heretofore required in the operation or method of raising and lowering derricks, are rendered completely unnecessary. These accessory adjuncts decreased the visibility of the worker or driller, of the working platform and hence interfere with efficient operation. In addition, these complements crowd the racked pipe, restrict the clearance in the derrick, and generally reduce the area of movement of the operator, which makes for unfavorable working conditions.

Another object of the invention is to provide a system or method of raising a derrick, in which the drill lines may be strung in advance of the erection and in which the derrick when erected, is ready for the drilling operation, without the need for stringing the blocks for drilling after the derrick is erected, it being necessary merely to remove the constant length line from the running block and to dispose it so as not to interfere with the drill line.

Further objects and advantages of the invention will appear from the following specification.

Referring to the drawing which is for illustrative purposes only,

Fig. 1 is an elevation view showing a form of my invention as applied, dotted lines showing a derrick in elevated position.

Fig. 2 is a plan view.

Fig. 3 is an elevational view of a form of gin pole or supporting structure.

A derrick of the four legged type is shown at 10. The legs 11, which, for purposes of description, may be designated as the front legs, are associated with a pivotal connection 12 which is mounted upon a base 13. The legs 14, which may be designated as the rear legs of the derrick 10, are arranged to rest on and be secured in any desirable manner to a suitable support, or shoe

2

plates 15, when elevated to upright position to maintain same in vertical position. Such support, however, forms no part of the present invention and therefore needs no further description. On the base 13 is a drum 16 arranged to be rotated by power devices or engines 17 which are attached to said base. A gin pole 18 secured to and upstanding from said base 13 is provided at the top with spaced sheaves 20 and intermediate sheave 21 for purposes presently appearing. Below the sheaves 20, sheaves 19 are mounted on the base 13.

By members 22 each connected at one end to the top of the gin pole 18 and at the other end 15 to said base 13, the gin pole is maintained in substantially upright position, which, as shown, is preferably in front of the rear legs 14 of the derrick. On the top of the derrick 10 is mounted a crown block 23 from which is suspended within the confines of the derrick 10 a running or traveling block 24, said block 23 and the block 24 carrying sheaves 25 and 26 respectively, over which are trained the usual cables 27. Lifting and lowering of the derrick 10 is accomplished 20 by a variable length cable or haul line 28 secured at one end to the aforementioned drum 16, or any other suitable cable pulling means, such as a truck, for example, and trained about the sheaves 25 of the crown block 23 and the sheaves 26 of the traveling block 24, the free or dead end of said haul line or variable length cable 28 being connected to a suitable anchor 13'. In the prone or horizontal position of the derrick, this haul line passes from the drum 16, over the sheave 21 30 on the top of the gin pole 18, then over the sheaves 25 and 26, respectively, of the crown and traveling blocks 23 and 24, and being finally secured to the anchor 13' on the base. Since the tension or pull on this haul line 28 in raising 35 the derrick from a prone to a vertical position is considerable and is attended by severe strain on the several members of the derrick, it is not only desirable, but highly important, that this tension on the haul line be reduced and that the stress 40 on the derrick members be considerably decreased. To accomplish this reduction in the line pull it is necessary that the tension or force applied to the haul line be distributed, divided, or considerably relieved, and so applied at a desirable point on the derrick that this supplementing force may work in conjunction with the haul line in multiple of the force or pull exerted thereby. This multiple force proceeds from the traveling block 24 which is provided with a connecting means shown as a hook 29 over which 45 50 55

is fitted the bight 38 of a constant length line or sling line 31. The branches of this sling line 31 pass under the lower spaced sheaves 19 of the gin pole 18 and then over the sheaves 20 in the top of the gin pole. The free ends of said sling line 31 are then made fast or secured to the rear legs 14 of the derrick or to a connection 14' on the outside of the derrick legs and at a point intermediate the length of the derrick legs 14. By this arrangement it is obvious that the pull or haul on the hoisting line 28 operating the traveling block will exert a tension or pull on the constant length line 31 in excess of the pull on the haul line 28, which excess is determined by the number of plies of cable trained over the crown and traveling blocks, and that this excess pull on the constant length line is transferred directly to the legs of the derrick concurrently and cooperatively with the pull on the variable length cable or hoisting line 28. In this way, where the crown block and traveling block are connected by lines or cables, the pull on the line 28 is materially reduced over the teachings of the prior art, with an attendant decrease in the stress in members of the derrick, and with an increased ease in raising the derrick to substantially vertical position. When so raised and the rear legs of the derrick are secured to the base, the sling line 31 is removed from the connecting means 29, and the variable length line 28, which is trained over the crown and traveling blocks 23 and 24, respectively, is then ready for the drilling operation.

The threading of the constant length line as described, which is looped over the connecting means 29 of the traveling block, to-wit: under the sheaves at the bottom of the gin pole, thence over sheaves at the top of the gin pole, and the connection finally to the outside of the derrick leg, enables the blocks to be strung ready for the drilling when the raising operation is completed.

I claim as my invention:

1. A system of moving a derrick from one position to another about a pivoting center for the derrick, comprising: a base upon which the derrick is mounted for pivoting movement; crown and traveling blocks carried by said derrick and adapted to be interconnected by plies of cable; cable pulling means; a variable length cable secured at one end to said cable pulling means trained about the sheaves of said crown and traveling blocks and having its other end anchored to said base; a gin pole provided with sheaves; and a constant length line connecting said traveling block and at least a leg of the derrick, said line running over said gin pole sheaves, intermediate its length, and connected to the leg of the derrick above the pivoting point thereof.

2. A means for moving a derrick from one position to another in an arcuate plane, comprising: a base; a derrick mounted thereon to have pivoting movement relatively thereto; crown and running blocks carried by said derrick and having sheaves adapted to receive plies of cable which are customarily trained about the sheaves of said crown and running blocks; a rotatable drum; a variable length cable secured at one end to said drum and trained about the aforementioned sheaves, the other end of said cable being anchored to said base; an upstanding support having sheaves; and a constant length line connecting said traveling block and at least a leg of the derrick, said line running over the sheaves on said support intermediate its length.

3. A lifting and lowering system for derricks comprising: a derrick; a base; a pivotal connection on said base for the bottom of the derrick to enable the derrick to swing about said connection from a substantially horizontal position to a substantially vertical position; a crown block on the top of said derrick; a traveling block within the derrick, each of said blocks having sheaves adapted to receive plies of cables which are customarily trained about the sheaves of said blocks; means to move said derrick about said pivotal connection, comprising a variable length cable, cable pulling means to which one end of said cable is connected, said cable being trained about the sheaves of said crown and traveling blocks and connected at its other end to said base; and a constant length line having one end thereof connected to the traveling block and the other end thereof connected to a leg of the derrick at a point intermediate the ends of said leg and operating in conjunction with said variable length cable to reduce the pull on said variable length cable.

4. A lifting and lowering system for derricks comprising: a derrick; a base; a pivotal connection on said base for the bottom of said derrick to enable the derrick to swing about said connection from a prone position to a vertical position; cable pulling means on said base; a sheave carrying crown block on the top of said derrick; a sheave carrying running block within said derrick and adapted to be suspended from said crown block by plies of cable; a hoisting line connected at one end to said cable pulling means and trained about said crown and running blocks; sheave means carried by the base and a constant length line having one of its ends connected to said running block, its intermediate portion running over said sheave means and its other end connected to an intermediate portion of the derrick and working in conjunction with said hoisting line.

5. An erecting system for portable derricks comprising: a derrick; a pivotal connection to enable the derrick to swing from a horizontal to a vertical position; a crown block in the top of said derrick and a running block within said derrick; cable pulling means; a variable length hoist line connected at one end to said cable pulling means and at the other end to an anchor, an intermediate portion of said hoist line being trained about said blocks; a gin pole carrying upper sheaves; lower sheaves supported below said upper sheaves; and a constant length line looped on said running block, the branches of said constant length line threaded over said lower and upper sheaves and the ends thereof being secured to the derrick legs.

6. A lifting and lowering system for derricks, comprising: a base; a derrick having its front legs pivotally connected to said base to enable the derrick to swing from a horizontal to a vertical position; means on said base to secure the rear legs of said derrick when said derrick is raised to elevated position; a variable length hoist line connected at one end to said base; cable pulling means to which the other end of said hoist line is connected, said hoist line extending over the upper end of said derrick and a portion thereof extending within the confines of said derrick; and a constant length line connected at one end to the portion of said variable length line within said derrick and at the other end to the rear legs of said derrick.

7. A lifting and lowering system for derricks,

comprising: a base; a derrick having its front legs pivotally connected to said base to enable the derrick to swing from a horizontal to a vertical position; means on said base to secure the rear legs of said derrick when said derrick is raised to elevated position; a line extending from the upper end of the derrick to the interior thereof; cable pulling means to which said line is connected to elevate and lower the derrick; an upright support; and a sling line passing under and over said support and having one end extended into and connected to said first named line and the other end connected to the rear legs of said derrick intermediate the length thereof, said sling line cooperating with said first named line for swinging said derrick about said pivot.

8. A lifting and lowering system for derricks

comprising: a base; a derrick pivotally connected to the base so that it may be swung between horizontal and upright positions; cable pulling means; a variable length line extending from said cable pulling means to the top of the derrick and thence down into the interior of the derrick; a support adjacent the lower end of the derrick; a sling line passing around said support and having one of its ends extending into said derrick and connected to the portion of said variable length line which extends down into the derrick from the top thereof, the other end of said sling line being connected to an intermediate portion of the derrick, said sling line cooperating with said first named line in swinging said derrick between said horizontal and upright positions thereof.

HOWARD D. HILBORN.
